UNITED STATES PATENT OFFICE.

JOHN I. CRANMER, OF CHICAGO, ILLINOIS, ASSIGNOR OF ONE-HALF TO
WILLIAM L. MILLER.

THERMOSTATIC VALVE.

No. 806,465.

Specification of Letters Patent.

Patented Dec. 5, 1905.

Application filed May 1, 1905. Serial No. 258,413.

To all whom it may concern.

Be it known that I, JOHN I. CRANMER, a citizen of the United States of America, residing at Chicago, in the county of Cook and 5 State of Illinois, have invented certain new and useful Improvements in Thermostatic Valves, of which the following is a specification.

My invention relates to improvements in 10 thermostatic valves, and is fully described and explained in this specification and shown in the accompanying drawings, in which—

Figure 1 is a central longitudinal section through my improved device. Fig. 2 is a 15 perspective view of the automatic disk, and Fig. 3 is a perspective view of the coupling which connects the two sections of the automatic disk.

Referring to the drawings, A is a valve-body, here shown as of the angle type, having openings a' , the opening a' being provided with a valve-seat a^2 . It will be obvious in the further description of my device that the valve-body could be modified to a 20 very great extent, if desired, the special features of my device residing not in the body, but in the valve proper. Secured to the upper end of the body is a sleeve B, which carries at its upper end an ordinary valve-bonnet C, in which is threaded a valve-stem D, packed in any ordinary way. I adopt the 25 construction herein illustrated for my valve, because the valve body and bonnet, substantially as here shown, can be purchased upon the open market at a very low price, and by 30 the use of the sleeve B the structure becomes perfectly adapted for use in my device. A further advantage of this construction lies in the fact that there are many valves now in use 35 which can be made automatic by adding the proper parts, in which case the body proper would be enlarged in size by the interposition of a sleeve. It will be obvious that in manufacturing the device on a large scale, 40 however, the body and sleeve would naturally be made in one piece. The lower end of a valve-stem D is provided with a head d , which enters a laterally-open recess in the upper head e of the upper section E of the 45 automatic disk, the lower section of which is designated by E' in the drawings. These 50 two sections of the automatic disk are composed of lengths of metal tubing, preferably brass, the adjacent ends of said tubes or sec-

tions being made in the form of flexible dia- 55 phragms e' e^2 , joined together by a central coupling E^2 , extending through the same and clamped in place by nuts e^3 . By this means the two sections of the automatic disk are made to communicate with each other, but 60 are not in communication with the outside air. The lower end of the lower section E' of the automatic disk is made in the form of a plate E^3 , which seats on the valve-seat a^2 under proper conditions. A rod F extends 65 from the plate e down through the coupling E^2 and carries at its lower end a plate f , which forms the lower abutment for a spring F' , the upper end of which bears against the dia- 70 phragm e^2 . Within the lower section of the casing is a body of liquid G, which has a boiling-point lower than 212° Fahrenheit—as, for instance, alcohol or a light hydrocarbon. The head e is of slightly larger diameter than the remainder of the automatic disk, thereby 75 forming a flange which is adapted to rest upon an annular shoulder b , formed upon the sleeve B. The disk is brought to its working position by screwing the valve-stem down until the head e of the disk rests upon the 80 shoulder b .

My improved device is particularly desirable in heating systems, and especially in car-heating systems, and its operation is substantially as follows: In starting the sys- 85 tem steam is admitted to the heating system and passes through the same to the valve, which is located in the discharge-pipe there- 90 of, permitting the steam to flow from the opening a' . Thereupon as the temperature 95 of the liquid in the automatic disk rises the internal pressure increases, forcing outward each of the two flexible diaphragms and eventually causing the disk to seat in the valve-seat a^2 . The valve then remains 100 closed until the temperature of the water of condensation, which accumulates in the dis- 105 charge-pipe, lowers sufficiently to cause the vapor in the disk to condense, whereupon the spring raises the bottom of the automatic disk, opening the valve, discharging the wa- 110 ter which has accumulated until steam is again discharged, whereupon the operation above described is repeated. The auto- 115 matic disks can be raised at any time to blow off the system or any water of condensation which may have collected.

My device is particularly advantageous,

owing to its simplicity of construction and the fact that the automatic disk is entirely within the valve, so as to make freezing impossible.

5 I realize that considerable variation is possible in the details of this construction without departing from the spirit of my invention, and I do not intend to limit myself to the specific form herein shown and described.

10 I claim as new and desire to secure by Letters Patent—

15 1. In a device of the class described, the combination with a casing having a passage therethrough, of a screw-threaded valve-stem and a disk supported on the end of the valve-stem and movable therewith, said disk being adapted to expand automatically when heated and seat itself.

20 2. In a device of the class described, the combination with a valve-body having a seat and a screw-threaded valve-stem, of an expanding hollow body secured to said valve-stem and movable therewith and arranged to engage with said seat, said body containing a 25 quantity of fluid which vaporizes at a temperature less than that of steam.

30 3. In a device of the class described, the combination with a valve-body having a seat, of an automatic disk within the same and having one end adapted to engage with said seat to close the valve, said automatic disk being composed of two communicating portions, the adjacent heads of which are made in the form of flexible diaphragms.

35 4. In a device of the class described, the combination with a valve body and seat, of an upper disk portion having a lower flexible diaphragm, a lower disk portion having an upper flexible diaphragm, a hollow coupling 40 connecting said flexible diaphragm, the

lower end of said lower disk portion being arranged to engage said seat, and a body of fluid within said disk portions adapted to vaporize at a lower temperature than that of steam.

45 5. In a device of the class described, the combination with a valve body and seat, of an upper disk portion having a lower flexible diaphragm, a lower disk portion having an upper flexible diaphragm, a hollow coupling connecting said flexible diaphragm, the 50 lower end of said lower disk portion being arranged to engage said seat, a body of fluid within said disk portions adapted to vaporize at a lower temperature than that of steam, a rod secured to the top of said upper disk portion and extending through said coupling and a spring supported by the lower end of 55 said rod and bearing on the top of said lower disk portion.

60 6. In a device of the class described, the combination with a valve-body having inlet and outlet openings, of a valve-seat adjacent to the outlet-opening, an expansible body supported between the inlet and outlet opening and arranged to seat itself upon said valve-seat to close the outlet-opening when heated. 65

70 7. The combination with a valve-body having a passage and a valve-seat, of a screw-threaded valve-stem and a thermostatic valve carried by and movable with said valve-stem and arranged to seat itself when heated upon said valve-seat.

In witness whereof I have signed the above application for Letters Patent, at Chicago, in the county of Cook and State of Illinois, this 21st day of April, A. D. 1905.

JOHN I. CRANMER.
